HOLDER FOR PARACHUTE PULL CORDS

Samuel H. Knight, Lancaster, Pa.

Application May 31, 1930, Serial No. 458,119

15 Claims. (Cl. 244—21)

The pull cord that releases the catch holding the parachute in its pack has been carried in various ways by the aviator. Usually the end of the cord was attached to a ring, and sometimes the ring was hooked to a part of the aviator's harness. The particular method of securing the end of the cord might seem unimportant, were not everything connected with parachute launching required to be certain, handy and easy to operate. Among the objects of the present improvement is to attach the cord springingly but removably to the aviator's clothing or harness. The device I have designed and constructed has a handle that can be grasped readily by the aviator, which is provided with a springing engaging element engaging with the aviator's harness or clothing and which may be pulled loose from them. It is attached to the pull cord.

The handle lies, and is retained within easy reach of the aviator, and can be readily gripped by the aviator, who, when he grips it, will easily disengage it from its connection with the aviator's clothing or harness, and pull the catch that retains the parachute in the pack.

A single continuous movement can effect all these purposes. The holder remains sufficiently securely connected to the aviator's person to assure the aviator he can, by merely reaching for the holder, find it and grasp it.

The use of a handle containing a springing engaging element engaging with retainers on the harness or clothing of the aviator, where the springing engaging element is attached to or forms part of the handle has many advantages.

To form on the dress or harness a yielding engaging element necessarily, at least in commercially available structures, requires the use of rubber elastics which are disintegrated readily. Mounting any engaging material of springing metal on the harness would be so objectionable in many ways, as to be commercially impossible. But, if a springing engaging element is positioned on or forms part of the handle and a non-elastic retaining element is positioned on the harness, the latter will require no rubber elastics, and the yielding and springing features may be entirely metallic if positioned on or forming part of the handle.

In the best form of my device of which I am at present aware the handle is made of spring wire, the handle portion of which forms a spring that can be grasped by the aviator's hand, and which urges springingly a pair of arms, also formed by the wire to the ends of a pocket. This preferred form of my

device I will proceed now to describe in detail.

Fig. 1 is an elevation of the handle showing the attachments to it of the pull cord. Fig. 2 is a like elevation showing the handle in a pocket on the harness of an aviator.

The pull cord 3 is attached in any suitable way to the handle. I have illustrated it as looped into the loop C formed by the parts 5 and 6 that form one of the clamping arms of the holder. The end of the pull cord 3 may be passed through the loop C formed by the parts 5 and 6 and turned back on and secured to itself. A binding wire 4 may be used to secure the end of the pull cord to the portion of the pull cord back of the loop C of the springing clamp arm. It may be bound by the binder 4 to this portion of the pull cord.

The handle is made of spring wire, the central portion of the wire forming the grip loop D and the ends the clamping arms that engage with the pocket. One side of the grip loop D has the two wires 1 and 2; the other side a single wire 19. From the grip loop, wires 1 and 2, extend the clamping arms. These clamping arms are formed in practice into two loops B and C, the portion 6 of a wire being turned back to the portion 5, at a. It may be soldered or brazed to it at that point.

In practice, the grip loop and the arm loops B and C lie substantially in the same plane. The clamping arms spread sidewise outward to engage springingly the ends of the pocket. It will be noted that the precise structure illustrated (to which however, I do not limit my invention) has some very particular advantages of construction. The grip loop D, has double wires, and on the outside of the handle, and one end of each wire bends inward to form the springing clamp arm, and the wires 1 and 2 are connected by the wire 9, which will lie partly in the pocket. The greater part of the holder is therefore contained in the pocket, leaving only a small part of the holder projecting from it.

The pocket 7, in which the holder is releasably retained, is formed preferably between a strip 18 secured by sewing to some part of the aviator's clothing or harness, very conveniently to one of the vertical straps A of the harness such as the loadstrap. It is closed, in practice, at the bottom by a row of stitches 16, and the length of the pocket decreases from its back towards its mouth. The ends may have reinforcements 8, 8, suitably sewed to the strap and the mouth of the pocket may have a reinforcement 9.

While the aviator is flying the holder keeps the pull cord always in a position that is readily

accessible and the holder is easily releasable. When the parachute is to be released the aviator grasps the holder by the grip loop D and pulls it from the pocket, and pulls the pull cord, and releases the parachute from the pack.

The device is very simple, but is susceptible to quite a number of changes without departing from my invention, which is not to be limited to less than what is defined by the annexed claims.

10 I claim:

1. In a holder for a parachute pull cord the combination with a pocket carried by the aviator, of a holder and a pull cord attached to said holder, said holder comprising in combination a grip loop and clamping arms, formed of springing wire, the clamping arms having free ends in springing engagement with the pocket.

2. In a holder for parachute pull cords the combination with a pocket carried by the aviator, 20 of a holder consisting of a grip loop and springing arms, formed from a single length of springing wire, the central portion of said wire forming a hand grip loop and the ends forming springing arms having free ends engaging with the ends 25 of the pocket, and a pull cord attached at one end to said holder.

3. In a holder for a parachute pull cord, the combination with a pocket having sides sloping inwards as they approach the mouth, and a holder having a hand grip loop and springing clamping arms having free ends springingly engaging with the said inclined ends of said pocket and a pull cord attached at one end to said holder.

4. The device as defined in claim 1, wherein the 35 clamping arms form loops, into one of said loops the end of the pull cord is secured.

5. The device as defined in claim 3, wherein the hand grip loop and the springing clamping arms consist of a single wire, the ends of said 40 wire forming the springing arms and the middle portion, the hand grip loop.

6. The device as defined in claim 2 wherein the springing clamping arms have each loops formed of the end of the wire turned backward and secured to a portion of said wire nearer the grip 45 loop.

7. The combination with a parachute harness and a pack therefor, of a release cord extending from said pack, of a handle member, with a hand grasping portion and free sides extending from 50 said hand grasping portion, the free end of said release cord connected to one of said sides, and means for releasably holding said member on said harness.

55 8. The combination with a parachute harness and a pack therefor of a release cord extending from said pack, of a handle, with a hand grasping portion and free sides extending from said hand

grasping portion, the free end of said release cord connected to one of said sides and means for releasably holding the free sides on said harness.

9. The combination of a release cord for a 5 parachute container and a handle therefor and a pocket for holding said handle, said handle having a hand grasping portion and free sides extending from said hand grasping portion, the free end of said release cord connected to one of said free sides, said free sides of said handle being 10 springingly held in said pocket.

10. The combination with the parachute pack and pull cord, and harness having retainers thereon, of a handle comprising freely movable side pieces springingly urged into engagement 15 with the retaining means on the harness, said side pieces being disengageable from the retainers on the harness by the outward pulling of the handle.

11. In a parachute pack opening assembly, the 20 combination of a pull cord for a parachute container, a handle for said cord, and a pocket for holding said handle, said handle having a hand grasping portion and free sides extending from 25 said hand grasping portion springingly urged into engagement with the walls of said pocket, the free end of said pull cord being connected to one of said free sides.

12. An assemblage of co-acting instrumentalities for holding releasably the pull cord to the harness of an aviator, comprising, retainers positioned upon the harness, and a handle attached to the pull cord and composed of a hand grasping portion, an attachment for the free end of the pull cord, and springingly actuated engaging 30 means positioned on said handle to engage yieldingly the retainers.

13. The co-acting assemblage defined in claim 12 wherein the retainers are formed by a pocket positioned on the harness the bottom of which 40 pocket is permanently longer than the length of the mouth of the pocket, which length of mouth is positively limited, the engaging means, when free, extending more widely from each other than the length of the pocket.

45 14. A cooperative assemblage for holding the handle of a parachute pack pull cord yieldingly attached to the harness, comprising a handle having springing engaging means attached to said handle, retainers fixedly and positively attached 50 to the harness and positioned thereon to engage with the springing engaging means on the handle, the handle being secured to the pull cord.

15. The assemblage defined in claim 14 wherein the retainers are formed by the ends of a 55 pocket positioned on the harness.

SAMUEL H. KNIGHT.
